No. 877,399.

PATENTED JAN. 21, 1908.

W. W. BRISSENDEN.
RELIEF VALVE FOR RADIATORS.

APPLICATION FILED MAR. 4, 1904.

UNITED STATES PATENT OFFICE.

WALTER WEBB BRISSENDEN, OF CHICAGO, ILLINOIS, ASSIGNOR TO NATIONAL STEAM SPECIALTY COMPANY, OF CHICAGO, ILLINOIS, A CORPORATION.

RELIEF-VALVE FOR RADIATORS.

No. 877,399.

Specification of Letters Patent.

Patented Jan. 21, 1908.

Application filed March 4, 1904. Serial No. 196,526.

To all whom it may concern:

Be it known that I, WALTER WEBB BRISSENDEN, a citizen of the United States of America, and resident of Chicago, Cook county, Illinois, have invented a certain new and useful Improvement in Relief-Valves for Radiators, of which the following is a specification.

My invention relates to valves adapted more particularly for use on steam radiators, but adapted also, of course, for use in various other connections.

Generally stated, the object of my invention is the provision of a simple and highly efficient relief valve for use on radiators in steam systems of that particular character in which the water of condensation is allowed to escape from the radiator through a special pipe or off-take, rather than to escape from the radiator and flow back through the steam pipe, as is the case in certain other systems.

A special object is the provision of a valve of this character in which both the valve-seat and the body of expansible or heat-responsive composition employed for automatically closing the valve as soon as the air and water have escaped are characterized by an improved construction and arrangement whereby both are readily removable as a unit from the casing or body-structure of the valve.

Another object is the provision of an improved construction and arrangement whereby the valve-seat and the body of expansible composition which constitutes the valve-plug, may be readily inserted in place and given what may be termed a rough adjustment relatively to each other, and whereby the said body of expansible composition or valve-plug may then, upon expanding under the influence of the steam, adjust itself bodily and thereby assume an accurate position with relation to the valve-seat.

A further object is the provision of an improved construction and arrangement whereby both the valve-seat and the body of expansible composition or valve-plug may be raised for the purpose of permitting the chamber in the valve-casing to free or clear itself of any sediment or dirt which may have accumulated therein.

To the foregoing and other useful ends,

my invention consists in matters herein-after set forth and claimed.

In the accompanying drawings—Figure 1 is a vertical section of a valve embodying the principles of my invention; Fig. 2 is a horizontal section on line 2—2 in Fig. 1; Fig. 3 is a side elevation of the upper portion of the valve-casing; Fig. 4 is a side elevation of the upper end-portion of the unitary structure comprising the valve-plug and valve-seat; Fig. 5 is a side elevation of the lower end-portion of said unitary structure.

As thus illustrated, my invention comprises an upright valve-casing A, provided with an enlargement a providing a valve-chamber a¹, and provided also with upper and lower and lateral threaded portions a², a³, and a⁴. The portion a⁴ can be connected in any suitable manner with the lower portion of the steam radiator, while the portion a³ can be connected with the drain or off-take pipe through which the water escapes from the radiator.

The bottom wall of the chamber a¹ is provided, preferably, with a seat a⁵ adapted to receive the beveled or tapered lower end-portion of the tubular and upwardly projecting valve-seat B. It will be seen that the upper end-portion of the said valve-seat is enlarged slightly to provide a shoulder b.

The tubular upper portion a² of the valve-casing is preferably provided with a sleeve or lining C, preferably of brass, and adapted to extend somewhat above the top of the portion a². This projecting upper-end portion of the sleeve or lining C is supplied or provided with longitudinal cuts at different points in its circumference, as shown more clearly in Fig. 3. A bushing C¹ is arranged inside the casing a² and outside the sleeve or lining C. As illustrated, the cylindric composition or valve plug D is preferably provided with a reinforcing sleeve or jacket E, and also with a metal cap or head-portion F. Both the sleeve or jacket E and the cap F can be secured to the upper end of the body of expansible composition or valve-plug D by means of a transversely inserted pin e. It will be observed that the sleeve E is preferably of such character that the lower end of the valve-plug D is exposed, and thereby adapted to expand and move toward and away from the upper end of the valve-seat

B. It will also be seen that the lower end portion of the said sleeve or jacket E is provided laterally with openings e^1 , and with an internally arranged collar or shoulder e^2 .

5 With this arrangement, it will be seen that the smaller diameter of the tubular valve-seat B fits the bore of the said collar or shoulder e^2 , and that the shoulder d is adapted to engage and bear upon the said shoulder e^2 , as will hereinafter more fully appear. Furthermore, the upper end-portion of the cylindric structure composing the valve-plug is preferably covered by a cap G screwed onto the upper end of the casing portion a^2 .

10 The tubular sleeve or jacket E can fit the lining C, and by giving the upper portions c of this lining a slight inward bend or spring, it is obvious that a sufficient grip or frictional contact will be maintained between the two 15 sleeves to hold the valve-plug in any desired position.

In attaching the valve to the radiator, it is simply necessary to insert the combined valve-plug and valve-seat structure until the 20 lower end of the valve-seat engages the seat a^5 . The valve-plug D, which has a sliding connection with the valve-seat through the medium of the lower end-portion of the sleeve or jacket E, can then be raised slightly so as 25 to lift the lower end of the expansible composition or valve-plug slightly above the upper end of the valve-seat. In use, the water escapes through the valve-chamber a^1 , through the opening e^1 , and thence down 30 through the bore of the valve-seat B, and through the off-take or drain-pipe connected to the bottom of the valve-casing. As soon as the air and water have thus escaped from the radiator, the steam then causes the valve- 35 plug D to expand and engage the upper-end of the valve-seat, and, if the expansion then continues after the lower end of the valve-plug engages the valve-seat, the entire valve-plug structure can, it will be seen, then shift 40 upwardly or adjust itself vertically until the expansion ceases. In this way, breakage or 45 other injury to the valve is avoided.

The brass sleeve or jacket C reinforces the body of expansible composition D, and 50 confines or limits the expansion of the composition or expansible material to endwise movement. In other words, the valve-plug can expand longitudinally, but not laterally, and thus all of the expansive force of the plug is 55 exerted in the right direction for opening and closing the valve. The entire cylindric structure, comprising the valve-plug and valve-seat, is readily removable through the top of the casing by simply unscrewing the 60 cap G. Also, as illustrated, the valve-plug and valve-seat can be lifted or raised, so as to leave the steam free to blow whatever sediment or other accumulation may have formed in the chamber a^1 out through the

opening a^6 , and thence through the drain or off-take pipe. Thus it is not only possible to readily remove and clean the valve-plug and valve-seat, but it is also possible to readily blow or eject all accumulations from the valve-chamber.

70

An automatic valve of this character is more especially adapted for use in low pressure systems. Should the valve-plug be displaced by abnormal expansion, it can then be restored to normal by hand.

75

This application covers an improvement on the invention shown and described in my application Serial Number 196,525, in which I have claimed broadly the use of a metal jacket surrounding the valve plug.

80

I claim as my invention:

1. In a valve of the character described, the combination of a valve-casing, an expansible valve-plug and a tubular valve-seat 85 slidably connected and organized into a unitary structure, which is readily removable from the casing.

2. In a valve of the character described, the combination of a valve-casing, an expansible valve-plug and a tubular valve-seat 90 suitably connected and organized into a unitary structure which is readily removable from the valve casing.

3. In a valve of the character described, the combination of a valve-casing having a 95 chamber apertured at its bottom, a tubular valve-seat having its lower end removably seated in said aperture, and an expansible valve-plug removably mounted in the casing and having its lower end arranged in position 100 to engage the top of said valve-seat, said valve-plug being frictionally held at its middle portion, and thereby adapted to have unlimited end-wise movement should it continue to expand after engaging said valve-seat.

4. In a valve of the character described, the combination of a valve-casing provided with a chamber apertured at its bottom, a tubular valve-seat having its lower end removably seated in said aperture, a metal tube extending upwardly and having its lower end telescopically connected with the upper end-portion of said valve-seat, and a body of expansible material inclosed by said tube and adapted to expand and engage the top of said valve-seat when subjected to heat, the whole forming a unitary structure readily removable from the casing.

110

5. In a valve of the character described, 120 the combination of a valve-casing, a valve-seat, and a body of expansible material mounted in said casing and having a yielding frictional connection therewith, whereby said body of expansible material may have unlimited end-wise movement and thereby adjust itself relatively to the casing should the expansion continue after it engages the said

125

valve-seat, said valve-seat being adapted to act as a stop to limit the expansion in one direction only.

6. In a valve of the character described, 5 the combination of a valve-casing, a valve-seat in said casing, and an expansible valve-plug adapted to coöperate with said valve-seat in opening and closing the valve, said valve-plug having a self-adjusting connection with the said valve-casing.

7. In a valve of the character described, 15 the combination of a valve-casing, a valve-seat in said casing, and a valve-plug of heat responsive or expansible material, said plug being provided with a metal jacket and having one end free to expand longitudinally, and having its other end provided with a metal cap secured to said jacket.

8. In a valve of the character described, 20 the combination of a valve-casing, a tubular valve-seat removably mounted in said casing, a metal tube having its lower end-

portion telescopically connected with the upper end-portion of said valve seat and provided laterally with openings, and a body 25 of heat-responsive or expansible material inclosed by said tube and having its lower end portion adapted to move toward and away from the said valve-seat when said material expands or contracts, the valve-seat and tube 30 being provided with mutually engaging shoulders adapted to prevent the separation of the valve-seat and tube when the same are withdrawn from the casing.

9. In a valve, a solid expansible valve-plug 35 and a tubular valve-seat, removable as a unitary structure.

Signed by me at Chicago, Cook county, Illinois, this 2nd day of March, 1904.

WALTER WEBB BRISSENDEN.

Witnesses:

SEVERINUS B. CHABOWSKI,
WM. A. HARDERS.

It is hereby certified that in Letters Patent No. 877,399, granted January 21, 1908, upon the application of Walter Webb Brissenden, of Chicago, Illinois, for an improvement in "Relief-Valves for Radiators," an error appears in the printed specification requiring correction, as follows: In line 85, page 2, the words "sclidably onnected" should read *slidably connected*; and that the said Letters Patent should be read with this correction therein that the same may conform to the record of the case in the Patent Office.

Signed and sealed this 4th day of February, A. D., 1908.
